UNITED STATES PATENT OFFICE

BLAMEY STEVENS, OF TEMASCALTEPEC, MEXICO

HYDRAULICALLY-OPERATED DIAPHRAGM PUMP

Application filed December 7, 1927. Serial No. 238,244.

This invention has to do generally with pumps, and is more particularly concerned with hydraulically operated diaphragm pumps wherein the actuating force is transmitted to the diaphragm through a body of fluid, which I chose to term "actuating fluid." The vibrations of the diaphragm, as set up by the variable pressure of the actuating fluid, cause pulsations of the fluid

5 to be pumped and, by the movement of suitable valves, cause the periodic flow of the last named fluid in a given direction.

Generally described, my pump includes a main chamber having inlet and outlet valves for the fluid to be pumped, a second chamber containing actuating fluid, a movable wall or diaphragm separating the two fluids, and means for varying the pressure of, or setting up pulsations in the actuating fluid.

An increase in actuating fluid pressure causes displacement of the diaphragm and a consequent displacement of a certain amount of main chamber fluid, the displaced fluid lifting the outlet valve and passing from the main chamber. At the same time, the increased pressure of the main-chamber-fluid holds the inlet valve seated. Upon subsequent pressure drop in the actuating fluid and the consequent return of the actuating fluid body and diaphragm to their initial positions, suction is created in the main chamber, closing the outlet valve, opening the inlet valve, and drawing a new charge of fluid into said main chamber.

Water, oil or air may be utilized as the actuating fluid, though oil is preferably used, especially when a piston is employed for producing the fluid pulsations, in order that said piston and its associated parts may be self-lubricated.

The means for producing pulsation of the actuating fluid may be of any suitable character, for instance, I may utilize a plunger adapted to be reciprocated through the actu-

ating fluid, and I have here shown such means, though this is not to be construed as limitative on the invention considered in its broader aspects. An understanding of the operation gained from this specific disclosure will render it equally understandable to those skilled in the art how the invention is applicable when other means are employed.

The device is capable of pumping liquids, 55 semi-liquids and gases; or may be in the nature of an air or gas compressor. It may be utilized to exhaust air or gases from a given receptacle to produce a partial vacuum therein.

In United States Letters Patent No. 1, 627,257 issued to me May 3, 1927, and entitled "Hydraulically operated diaphragm pump," I have disclosed a pump of the nature generally described above and have 65 there pointed out many of the outstanding advantages thereof. It will be unnecessary to repeat them here, for they apply equally well to the instant disclosure.

Now it is necessary to continued efficient 70 operation of this type of pump that the quantity of actuating fluid in the actuating fluid chamber be kept substantially constant, in spite of the fact that there are bound to be leakages therefrom. Otherwise, there 75 is a gradual change in the mean position of the diaphragm or air is admitted to replace the lost fluid, with a coincident lowering of efficiency, as will be readily understood.

In the aforesaid patent I have shown several means for replenishing the actuating fluid and for extracting air from the actuating fluid chamber. In the present application I have shown other means for accomplishing these results and it is to this feature that the present claims are drawn. The means here disclosed are such that the pump with its automatically acting replenishing means is reduced to utmost simplicity and yet acts with highest efficiency. However, 90

the means may be discussed to better advantage in connection with the following detailed specification, reference being had to the accompanying drawings, in which the figure is a medial cross-section through a pump embodying my invention.

First, without regard to my improved means for replenishing the supply of actuating fluid, I will describe the general nature and operation of the pump.

A main or valve chamber 10 and secondary or actuating chamber 11 are defined by sections or housings 12 and 13, respectively, of pump casing 14. Housing 13 is in the nature of a dome secured to housing 12 by bolts 11a.

A movable barrier or diaphragm 8 serves as a partition between chambers 10 and 11. Preferably, this diaphragm is marginally anchored, for instance, by being clamped between housings 12 and 13. This diaphragm may be of any suitable material (rubber, for instance) having the requisite quality of elasticity and preferably, resiliency. In its broader aspects, however, the invention includes the embodiment of a movable wall or separator plate entirely unattached to the side walls of the pump casing, though preferably (but not necessarily) in fluid tight engagement therewith.

In order to limit the extent of diaphragm movement, thus preventing said diaphragm from being over-stressed, I provide grids or perforated stop plates 9 and 9a above and below the diaphragm, respectively, both said plates being spaced from the diaphragm when the latter is unflexed. Preferably, the plates are of arcuate cross-section, as clearly illustrated, in order that they may be substantially complementary to the diaphragm when the latter is flexed in either direction.

Pipes 15 and 16, respectively, lead to and from chamber 10, usual inlet valve 17 and outlet valve 18 serving as movable closures for pipes 15 and 16, respectively.

A piston or plunger 19 is adapted to be reciprocated through chamber 11 by any suitable mechanism, for instance, crank arrangement 20 which is adapted to be actuated from any suitable power source or prime mover (not shown). Piston 19 enters chamber 11 through a usual stuffing box 21.

Fluid B which is to be pumped (and which may be water, slime, acid, etc.) normally fills chamber 10; while actuating fluid A, oil, for instance, completely fills chamber 11. When oil is used as the actuating fluid, it performs the additional function of lubricating the piston and stuffing box. On the other hand, since diaphragm 8 holds fluid B from direct contact with the piston and stuffing box, the device is capable of pumping fluids which are de-

structive or detrimental to said piston and stuffing box.

In order more clearly to differentiate between the actuating fluid and the fluid to be pumped, I will hereinafter refer to fluid A as "oil" and to fluid B as "water," though these references to particular fluids are not to be considered as inferences that the pump does not function equally well to handle fluids having characteristics different from those named.

As before stated, and contemplated as being included within the scope of my claims, I may employ any suitable means for producing pulsations in or surges of fluid A, but I have chosen to illustrate reciprocatory piston 19 as a convenient and satisfactory pulsation producing means, and I will describe the operation of the device by referring to the mechanism shown, whereupon its operation in connection with other forms of pulsation producing means will be readily understandable.

Assuming piston 19 is at the limit of its up-stroke, that chamber 10 is filled by fluid B, and that chamber 11 is filled by fluid A, the downstroke of the piston causes displacement of fluid A and a consequent displacement or downwardly directed flexure of diaphragm 8. In its downward movement, the diaphragm 8 displaces a certain amount of fluid B, valve 18 lifting to allow the displaced water to pass into pipe 16.

Upon a subsequent up-stroke of the piston, oil A and diaphragm 8 return to their initial positions, tending to create a vacuum within chamber 10 and hence closing valve 18 (the valve closing action may be aided by spring means, not shown, or gravity, if desired) opening valve 17 and admitting or drawing a replenishing charge of water from pipe 15 into chamber 10. When diaphragm 8 is resilient as well as flexible, it aids in the return of fluid A to its initial position.

Thus, repeated pulsation or surges of fluid A bring about the alternate admission and expulsion of fluid B to and from chamber 10, the inlet and outlet valves serving to direct the flow in a given direction.

There is bound to be loss of fluid A through stuffing box 21, and, if no compensating means were employed and the device were operated as a force pump, this loss of fluid would result in a gradual change in the mean position of the diaphragm, that is, said mean position would gradually approach grid 9. Under the same circumstances, if the device were operating as a suction pump, the oil lost through the stuffing box would be replaced by air entering through said box. Therefore, in the absence of compensating means, this loss of actuating fluid would cause a loss in pump efficiency and finally render the pump inoper-

90

ative. I have here shown a most simple and effective means for overcoming this problem.

Assume first that the level L of the source 5 of supply or body B' of the fluid to be pumped is at given vertical distance from diaphragm 8, pipe 15 dipping into body B' at a point below level L. I then provide a reservoir R which contains a body C or re- 10plenishing source of supply of actuating fluid, the vertical distance of the reservoir from the pump having certain relationship with said given distance, as will be made apparent later. A pipe 22, preferably joint- 15less to eliminate all danger of leakage, ex- tends from below the level L' of body C to housing section 13 where it opens at 23 to chamber 11. A back-pressure valve 24, preferably, though not necessarily, immersed 20in the fluid within the reservoir, is provided in pipe 22 to prevent movement of fluid from said pipe back to reservoir R. It will be evident that both body B' and body C are exposed to atmospheric pressure.

Now the relative effective heights of pipes 25 15 and 22 are such that during the suction stroke of the pump and with given fluids used the resultant effective pressure of the fluid to be pumped is greater than that of 30 the replenishing supply of actuating fluid, the relative heights therefore depending on the relative specific gravities of fluids B' and C. Thus, during periods when re- plenishment of fluid within chamber 11 is 35 unnecessary, on the upstroke of piston 19, it is assured that diaphragm 8 will rise to its mean position and that fluid B' will flow into chamber 10, rather than actuating fluid from reservoir R rising through pipe 40 22 and entering chamber 11 to hold the dia- phragm down. If the actuating fluid in reservoir R be of less specific gravity than that of the fluid to be pumped (as is true in the illustrative case made here wheré the 45 actuating fluid is oil and the fluid to be pumped is water) level L' must be lower than level L, the exact differential in height or hydrostatic head varying with the individual characteristics of the particular 50 fluids, factors of resistance, etc., but always being sufficient to insure proper action. Of course, where the actuating fluid is of greater specific gravity than the fluid to be pumped, level L' may be above level L.

Now assume that there be escape of oil 55 through stuffing box. Diaphragm 8 is then drawn against grid 9 during the upstroke of the piston and before said piston completes said stroke. The continued upward move- 60ment of the piston to the end of its stroke tends to create a vacuum within chamber 11 and results in the flow under atmospheric pressure of replenishing fluid from reser- 65voir R through pipe 22 into chamber 11, the prior leakage from said chamber thus being

automatically compensated and the normal efficiency of the pump continuing unimpaired.

It will be recognized that in the pump the effective intake pressure of the fluid to be pumped is substantially the same as the pressure of the actuating fluid during the intake stroke. Hence the compensating means may be considered as a fluid supply connected with the actuating chamber 11 at 70 an effective pressure less than the pressure of the actuating fluid during the intake of the fluid to be pumped. 75

In order to prevent the flow of air through the stuffing box to chamber 11, I prefer to provide a fluid seal thereabout. This may conveniently be done by forming a cup-like flange 25 at the upper end of housing section 13 around stuffing box 21. This cup is kept filled with fluid S at all 80 times, the actuating fluid (usually oil) leaking through the stuffing box tending to preserve a sufficient quantity therein, once it has been initially filled. The operator is 85 thus being relieved of this refilling duty. 90

In order that the actuating fluid may not be wasted and so reservoir R need not often be refilled, a drain tube 26 may lead from the cup, at a point above the stuffing box, to reservoir R. The actuating fluid may 95 thus be used over and over again, passing through the following cycle: reservoir R, pipe 22, chamber 11, stuffing box 21, cup 25, drain 26 and reservoir R.

It will be understood the drawings and 100 description are to be considered merely as illustrative of and not restrictive on the broader claims appended hereto, for various changes in design, structure and arrangement may be made without departing from 105 the spirit and scope of said claims.

I claim:

1. In a pump, a casing defining two chambers, a movable barrier between the chambers, a body of actuating fluid in one of the chambers, inlet and outlet valves adapted to control the passage of the fluid to be pumped into and out of the other chamber, means for producing pulsation in 110 said actuating fluid in a manner to recipro- ciate said barrier, and means for replenishing the supply of actuating fluid to com- pensate leakage losses thereof, said last- 115 mentioned means comprising a fluid supply connected with said one chamber and hav- ing an effective pressure less than the pres- 120sure of the actuating fluid during the intake of the fluid to be pumped.

2. In a pump, a casing defining two cham- bers, a movable barrier between the cham- bers, a body of actuating fluid in one of the chambers, inlet and outlet valves adapted to control the passage of the fluid to be pumped into and out of the other chamber, 125 a plunger movable through the casing and 130

said one chamber toward and away from the barrier to produce pulsation in said actuating fluid in a manner to reciprocate said barrier, means for replenishing the supply of actuating fluid to compensate leakage losses thereof, said last-mentioned means comprising a fluid supply connected with said one chamber and having an effective pressure less than the pressure of the actuating fluid during movement of the plunger away from said barrier.

In witness that I claim the foregoing I have hereunto subscribed my name this 23rd day of November, 1927.
